UNITED STATES PATENT OFFICE.

ARTHUR ADAMS, OF BALTIMORE, MARYLAND.

STUMP PULLER.

Application filed July 1, 1924. Serial No. 723,460.

To all whom it may concern:

Be it known that I, ARTHUR ADAMS, a citizen of the United States, residing at Baltimore city, State of Maryland, have invented 5 certain new and useful Improvements in Stump Pullers, of which the following is a specification.

This invention relates to stump pullers and has special reference to a portable 10 stump puller designed for operation by horse or man power or the like.

One important object of the invention is to improve the general construction of devices of this character.

15 A second important object of the invention is to provide an improved portable stump puller wherein the pulling mechanism may be shifted about a vertical axis to any desired angular relation with the supporting 20 mechanism.

A third important object of the invention is the provision of improved means for raising the pulling mechanism to elevated position while turning on said axis.

25 A fourth important object of the invention is the provision of a novel winding drum arrangement in such a machine designed to effect a pull back movement of the stump cable and stump.

30 With the above and other objects in view as will be hereinafter apparent, the invention consists in general of certain novel details of construction and combinations of parts hereinafter fully described, illustrated 35 in the accompanying drawings and specifically claimed.

In the accompanying drawings like characters of reference indicate like parts in the several views, and:

40 Figure 1 is a side elevation of the improved stump puller.

Figure 2 is a plan view thereof.

Figure 3 is a section on the line 3—3 of Figure 1.

45 Figure 4 is a section on the line 4—4 of Figure 1.

Figure 5 is a detail section through a certain clutch used herewith.

50 Figure 6 is a detail of the capstan pawl and ratchet mechanism.

Figure 7 is a detail of a certain brake forming part of the invention.

Figure 8 is an edge view of said barke.

55 Figure 9 is a plan view of the lower part of the turntable and its elevating mechanism.

Figure 10 is a side view of the operating lever for the elevating mechanism and its connections.

Figure 11 is a diagram showing the manner of pulling a stump with this device.

The mechanism of the invention is mounted on a platform 10 which is supported between a pair of hollow, box like sled runners 11, the platform being turned up at its 65 ends to prevent digging into the ground. There is thus provided in the support, a central well and in this well is mounted a vertically movable short cylinder 12 having a 70 diaphragm or base plate 13 extending thereacross, the base plate being provided with an annular groove forming a ball race for the bearing balls 14. Beneath this base plate 13 are provided pairs of links 15 which have their lower ends pivotally connected to 75 lugs 16 fixed to the platform 10. The upper ends of each pair of links are connected by a tie bar 17. These tie bars 17 are connected at one end of each by a cross bar 18 and on these bars rests the base plate 13. By an 80 inspection of Figure 3 it will be seen that movement of said tie bars to the left in that figure will effect elevation of the base plate.

In order to so move the tie bars the cross bar 18 has connected thereto one end of a 85 link 19 which extends outwardly through one of the runners and has its outer end connected to one arm 20 of a toggle or elbow joint, said arm being pivoted at one end to a lug 21 fixed to the side of the runner. So 90 the other end of this arm 20 is pivoted on one end of a second toggle arm 22 the remaining end of which is pivoted to a rod 23 movable slidably through guides 24 fixed to said runners. The remaining end of this 95 rod is linked to a hand lever 25 which has its lower end pivoted in turn to the runner. By this means movement of the hand lever will effect raising or permit dropping of the base plate in accordance with the direction of 100 such movement.

On the balls 14 is supported a turn-table 26 which is held in the upper end of the cylinder 12 and on this turn table is mounted the main frame of the machine which 105 includes lower longitudinal angle bars 27 and upper longitudinal angle bars 28 connected at their extremities by corner posts 29. At their central parts the bars 27 are connected by a transverse member 30 in 110 which is journaled the lower end of a vertical shaft 31 preferably having its lower

part square in cross section. Carried by the upper bars 28 is a housing 32 concentric with the shaft 31 and mounted on this shaft is a lower clutch member 33 which fits in the housing 32 which thus forms an upper bearing for said shaft. This clutch member is in the form of a toothed face clutch and cooperates with an upper clutch member 34. The upper clutch member is slidably mounted for vertical movement on rods 35 provided with heads 36 which rest on the top of the housing 32, the clutch being guided in vertical movement by the fitting thereof on the round upper end of the shaft 31 on which it may both slide and rotate. The rods 35 are also provided with offset heads 37 having journal portions 38 where-to are pivoted the upper ends of links 39. The lower ends of these links are pivoted to the sides of the upper clutch member and have each an operating handle or lever 40 by means of which the links may be rotated to lift the upper clutch members out of clutching engagement with the lower clutch member. Carried by the upper clutch member is a sweep 41 by means of which the upper member may be rotated.

On the upper and lower end of the squared portion of the shaft 31 are mounted the gears 42, the upper gear being part of the lower clutch member. These gears mesh with idler gears 43 carried by a vertical shaft 44 and the gears 43 mesh in turn with the gears 45 fixed on a vertical drum shaft 46 carrying a vertical stump pulling drum 47.

Similarly the other end of the frame is provided with a vertical drum shaft 48 whereon is mounted a hauling or pull back drum 49.

On the upper end of the shaft 48 is mounted a gear 50 and on a vertical idler shaft 51 is mounted an idler gear 52 which normally is displaced downwardly from meshing position with respect to the gear 50 but which may be raised to such meshing position by means of a shipper lever 53 which is provided with a fork end 54 engaging a shipper collar 55 on the shaft 51. The lever 53 is provided with a latch 56 working over a notched segment 57 to hold the lever adjusted.

The idler 52 normally meshes with a gear 58 formed on the upper clutch member but it will be obvious that raising this clutch member will disengage the gear 58 from the idler and that lifting of the latter, under these conditions, will bring the gears 50 and 58 into operative relation.

Fixed on the shaft 31 is a ratchet member 59 provided with radial teeth 60 where-with engage pivoted pawls 61 which are connected to an operating lever 63 by flexible strands 64 running over idlers 65. Also on the shaft 48 is fixed a brake drum

66 surrounded by a brake band 67 one end of which is connected to a brake wheel 68 fixed on a shaft 69. This shaft carries at its outer end a brake lever 70 provided with a latch 71 working over a toothed segment 72.

In operation cables 73 and 74 are provided for the stump pulling and pull back drums respectively, these two being preferably connected as shown in Figure 11 and there is also provided an anchor rope 75 which has its ends provided with loops engageable on anchoring hooks 76.

The manner of raising the stump puller is as follows:

The machine is transported to a suitable position near the stump to be pulled, preferably in a line between such stump and a tree or the like adapted for use as an anchor. The lever 25 is next used to raise the base plate and permit the main frame, which normally lies between the runners, to be swung into position in alignment with the stump whereupon the lever 25 is released so that the frame rests in said runners.

The anchor and pulling ropes are now adjusted and the upper clutch member, now engaged with the lower clutch member, is rotated by the sweep and thus effects winding of the cable 73 on the drum 47, the operation being continued till the stump is pulled. The stump may then be pulled back out of the way if further operations by means of the cable or rope 74 are desired, the main clutch being released and the gear 52 raised to permit actuation of the drum 49.

There has thus been provided a simple and efficient device of the kind described and for the purpose specified.

It is obvious that minor changes may be made in the form and construction of the invention without departing from the material spirit thereof. It is not, therefore, desired to confine the invention to the exact form therein shown and described, but it is desired to include all such as properly come within the scope claimed. For instance it is to be noticed that the present construction provides that the upper member of the clutch has its central portion forming a capstan 77, and that this may be omitted without in any way affecting the other parts of the machine.

Having thus described the invention, what is claimed as new, is:

1. In a device of the kind described, a supporting and transporting structure, a main frame, a vertically movable turntable mechanism supporting the main frame on said structure, elevating means for the turntable mechanism, and a rope winding mechanism carried by the main frame.

2. In a device of the kind described, a supporting and transporting structure including a sled bottom and laterally disposed runners extending above said bottom, a turn-

table mechanism mounted between said runners and arranged for vertical movement, elevating means for said turntable operatively connected thereto, a main frame supported by the turntable mechanism and normally resting between the runners, said elevating means being arranged to lift the turntable sufficiently to permit rotation of the main frame on the supporting structure, and 10 stump pulling apparatus supported by the main frame.

3. In a device of the kind described, a supporting and transporting structure including a sled bottom and laterally disposed 15 runners extending above said bottom, a turntable mechanism mounted between said runners and arranged for vertical movement, elevating means for said turntable operatively connected thereto, a main frame supported by the turntable mechanism and normally resting between the runners, said elevating means being arranged to lift the turntable sufficiently to permit rotation of the main frame on the supporting structure, 20 and stump pulling apparatus supported by the main frame, and including a winding drum at one end of the main frame, anchoring means at the other end and means to rotate the winding drum.

30 4. In a stump puller, a main frame, a main shaft disposed centrally of the length of the machine, a clutch member fixed on

said shaft, a second clutch member rotatable on said shaft and slidable longitudinally thereof, clutch shifting mechanism for said second member, a winding drum supported in said frame, gearing connecting the shaft and drum, a second winding drum supported in said frame, and means to connect the second winding drum operatively to the second clutch member upon movement of the latter to unclutched position.

5. In a stump puller, a main frame, a main shaft disposed centrally of the length of the machine, a clutch member fixed on said shaft, a second clutch member rotatable on said shaft and slidable longitudinally thereof, clutch shifting mechanism for said second member, a winding drum supported in said frame, gearing connecting the shaft and 45 drum, a second winding drum supported in said frame, a gear on said second clutch member sliding and rotating therewith, a gear on the second winding drum in edge alignment with the clutch supported gear 50 upon movement of the second clutch member to unclutching position, an idler gear movable into and out of mesh with the drum gear, said idler also meshing with the clutch gear upon movement of the second clutch 55 member to unclutched position.

In testimony whereof I affix my signature.

ARTHUR ADAMS.
